APPARATUS FOR GRINDING NON-CYLINDRICAL SURFACES

Elman R. Dunn and Donald F. Price, Waynesboro, Pa., assignors to Landis Tool Company, Waynesboro, Pa.

Application February 2, 1951, Serial No. 209,160

5 Claims. (Cl. 51—101)

1

This invention relates to cam grinding machines, particularly to the type of cam grinder which automatically grinds successive cams on a camshaft.

An object of this invention is to provide means for automatically grinding successive cams on a camshaft where said successive cams are tapered in opposite directions.

A further object is to provide means for changing the angular relation between grinding wheel and work each time an unground cam is moved into grinding position.

A further object is to provide hydraulic means for swivelling the wheelbase.

A further object is to provide a swivel point located relative to the grinding wheel so as to cause a minimum of dislocation of the grinding wheel relative to the work when swivelling from one position to another.

The drawing shows a combined electric, hydraulic and mechanical diagram showing the essential elements of the invention and their relation in the combination.

Numerical 10 indicates the work carriage of a grinding machine. The motor for traversing said carriage consisting of a cylinder 11 and a piston 12 slidably mounted in said cylinder. A piston rod 13 on said piston may be attached to said carriage in any suitable manner (not shown). A work piece 14 is rotatably supported on carriage 10 by headstock 15 and footstock 16.

Fluid under pressure for moving said carriage is directed to one side or the other of piston 12 by a reversing valve 20 through lines 21 and 22. Another portion 23 of valve 20 performs a function to be described later.

A by-pass valve 30, when in central position, connects lines 21 and 22 through lines 31 and 32 respectively so that carriage 10 may be actuated by hand without being obstructed by a locked body of fluid. Said by-pass valve also has another section 33 that directs fluid to a mechanism, which will be described later.

Said reversing valve and said by-pass valve may be actuated simultaneously through a combination of levers consisting of a U-shaped lever 40 having one side longer than the other, the longer side having a knob for manual actuation of said lever. Said lever is pivoted at the lower left-hand corner thereof on a shaft 41. The short side of said lever is connected to one end of by-pass valve 30. A projecting member 80 on lever 40 engages and operates headstock limit switch 81 for starting headstock motor 82.

2

A second lever 50 is located behind the short side of lever 40 and pivoted at 51. The upper end of lever 50 is connected to a horizontally slideable member 52 in which a plunger 53 is slideable vertically. The lower end of lever 50 is connected to reversing valve 20. When plunger 53 is in a notch, it acts through member 52 to locate reversing valve 20 in a neutral position.

A pin 42 in the short side of lever 40 extends through a hole 54 in lever 50. Said hole is about three times the diameter of the pin 42. A pair of pins 55 and 56 is slidably mounted in lever 50 so that they extend at right angles to and engage pin 42. Movement of pins 55 and 56 is restrained by springs 57 and 58, secured to lever 50 near its pivot point and extending downwardly to engage pins 55 and 56. Thus, when lever 40 is moved to right or to left, pin 42 causes a corresponding movement of lever 50 about its pivot 51. The upper end of lever 50, being connected through sliding member 52 to plunger 53, might cause a lateral movement of said plunger except for the fact that a reduced portion 59 on said plunger is normally in engagement with any one of several notches 60 or 60' in a spacing bar 61 on carriage 10. When so restrained, the movement of lever 40 results only in shifting the pins 55 and 56 against springs 57 and 58 respectively.

When lever 40 is placed in the right-hand position, pin 42 pushes pin 56 to the right against spring 58. When plunger 53 is withdrawn from the spacing bar, lever 50 is released; and spring 58 causes it to move in a counterclockwise direction and shift reversing valve 20 to the right. The carriage moves from left to right; and when the plunger drops in the next notch, the movement of the carriage carries it a short distance in the same direction so that through sliding member 52 it shifts lever 50 in a clockwise direction and moves valve 20 to the left until it shuts off the supply of fluid to cylinder 11 to stop the carriage in position for grinding another cam.

The means for manually withdrawing plunger 53 consists of a lever 100 which is loosely coupled to bell-crank 102, and both are mounted on shaft 101. Bell-crank 102 extends horizontally into operative engagement with plunger 53, and arm 103, also a part of bell-crank 102, extends downwardly between valve member 104 and piston rod 105 from piston 106 and cylinder 107. A further extension of arm 103 is connected to a yoke 108, which is slidably connected to adjust-

ing screw 161 in the stem 162 of valve 163. By this arrangement, lever 103 can be moved to withdraw plunger 53 and at the same time shift valve 163 only enough to place it in the left-hand position shown in the drawing. The extension of arm 103 also serves to engage exhaust valve 170 to shift it to the left against spring 171.

Valve 104 controls the movement of the grinding wheel support, and also serves as a medium for moving arm 103 and associated parts in a counterclockwise direction by means of spring 108. When so moved, arm 103 through bell-crank 102 moves plunger 53 upward so that the reduced portion 59 thereof may enter one of the notches 60 or 60' when properly aligned. When arm 103 and plunger 53 are actuated by timer piston 106 to withdraw plunger 53 from notched bar 61, fluid for operating said timer piston is directed to the head end of cylinder 107 by valve 115 which is shifted to a closed position by a solenoid 116 against the action of spring 117, during actual grinding time.

Solenoid 116 is energized or deenergized, as the occasion requires, at predetermined intervals by means of a timing mechanism 118. Fluid under pressure for operating the various mechanisms is supplied by a pump 120 through line 121 to reversing valve 20 from which it is directed alternately through lines 21 and 22 to opposite ends of cylinder 11. Line 123 connects line 121 with valve 104 around which fluid passes through line 124, valve 110, and line 126 to portion 23 of reversing valve 20. From lines 124 and 126 a supply of fluid under constant pressure is thus always available at said reversing valve, from which it might be directed alternately through line 127 or 128 to line 129. Fluid under pressure in line 129 acts on valve 130, shifting it upwardly and uncovering line 131 leading to the left-hand section 33 of by-pass valve 30. In any position of said by-pass valve except the left-hand position, said fluid would be directed through line 132 to the left-hand end of valve 110. The force exerted on said valve by said fluid plus that exerted in the same direction by spring 135 is greater than the pressure exerted against the opposite end and, therefore, shifts said valve to the right.

Fluid from line 121 is also directed through line 140 to the left-hand end of cylinder 107. Pressure is available constantly in this end of the cylinder so that when the opposite end is connected to an exhaust passage, the piston will be moved to the right.

Another supply of fluid under pressure from line 121 passes through line 141 to solenoid-operated valve 115. When said valve is in the right-hand position, it directs said fluid through line 142, check valve 143, and line 144 to the head end of cylinder 107. When by-pass valve 30 is in the left-hand position, the fluid supplied to the left-hand end of valve 110 is blocked; and said valve remains in the position shown. In this position of valve 110, pressure is admitted to lines 142 and 149 through valve 115, and thence through valve 143 to line 144 to cylinder 107.

As soon as by-pass valve 30 is shifted to central or right-hand position, fluid under pressure from line 131 is directed through line 132 to shift valve 110 to the right, connecting the head end of cylinder 107 through line 144 and line 145 with line 148, which is an exhaust passage, thus permitting the constant supply of fluid under pressure in line 140 to reset piston 106.

A grinding wheel 180 is rotatably mounted in

75

a wheel support 181, which in turn is slidably mounted on slide member 182. Slide member 182 is slidably mounted on a bed (not shown) for swivelling movement about a vertical axis 183, which passes through the central plane of the grinding wheel at a point between the grinding wheel spindle and the point of contact of the wheel with the work piece. The swivel point is preferably as close to said point of contact as circumstances permit. The means for moving wheel support 181 toward and from the work consists of a rapid feed piston 190 and a slow feed piston 191. This type of feed is described in detail in Patent No. 2,313,479, granted March 9, 1943.

The means for swivelling the slide member 182, and wheel support 181 consists of a cylinder 195, mounted on a bed (not shown) and having a piston 196 slidably mounted therein. Piston rods 197 and 198 extend through the ends of said cylinder to engage brackets 199 and 200 on slide member 182. Adjusting screws 201 and 202 determine the extent of movement of slide member 182 about swivel point 183.

Operation

Assuming carriage 10 to be in the extreme left-hand position with portion 59 of plunger 53 against stop 62, lever 40 is moved to the right.

30 Valve 20 is shifted to the right also, as is valve 30. With lever 40 in this position, projecting member 80 thereon closes headstock limit switch 81, energizes relay 83 which closes contact 84 to complete the circuit to headstock motor 82. In the right-hand position, valve 20 directs fluid under pressure from line 121 through line 22 to the head end of cylinder 11, causing piston 12 to move carriage 10 to the right until portion 59 of plunger 53 drops into the first notch 60' in response to the action of spring 108 transmitted through valve 104, arm 103, shaft 101, and arm 102.

When portion 59 of plunger 53 drops into the first notch 60', lever 100, moving in a counterclockwise direction in response to the action of said spring 108, acts through yoke 130 to move along adjusting screw 161 until it engages stem 162 of valve 163 and moves said valve to the right so that ball 213, pressed by spring 214, slips out of groove 211, which locates said valve in the left-hand position, and into groove 212, which locates said valve in the right hand position. Counterclockwise movement of lever 100 releases valve 170, which is moved to its right-hand position by spring 171. In this position, fluid from the rod end of cylinder 11 is prevented from discharging through line 172 and through said valve to exhaust passage 173. Line 172 is connected to exhaust 173 through throttle valve 174. This cushions the stopping of the carriage after plunger 53 drops into one of the notches in spacing bar 61.

In the right-hand position of valve 163, fluid under pressure from pump 120, line 121, and line 210 is connected to line 215, leading to the lower end of cylinder 195 and causing piston 196 to move upwardly to engage bracket 199 on slide member 182, thus shifting said wheel support in a counterclockwise direction to place wheel 180 in the dotted line position shown for grinding a tapered surface corresponding to the angular position of the grinding wheel 180. When slide member 182 is thus swivelled, guide surfaces for said support, which are on said slide 182, are also shifted so that, in the new position, the wheel

may be fed in a direction at right angles to the tapered surface which it is to grind.

Carriage 10 continues to move after the plunger has entered the notch until the side of the notch engages said plunger, shifting the plunger to the right. This movement is transmitted through sliding member 52 to lever 50, moving said lever in a clockwise direction and shifting valve 20 to the left until line 121 is blocked, thus preventing further flow of fluid under pressure to cylinder 12 and stopping the movement of carriage 10.

As indicated above, the counterclockwise movement of lever 100 is effected by spring 108, shifting valve 104 to the right in engagement with the extension 103 of lever 100. In the right-hand position of valve 104, fluid under pressure from line 121 enters said valve through line 123 and is directed by said valve through line 220 to the head end of the piston 190, initiating the rapid positioning movement of wheel support 181 in a direction determined by the position of slide 182. At the same time, a differential pump type fluid supply, such as shown in Patent No. 2,509,368, granted May 30, 1950, serves to supply fluid under pressure at a measured rate to the head end of slow feed piston 191. Said system consists of two pumps 230 and 231 which may be of different displacement or operated at different speeds so that pump 231 discharges a supply smaller in volume than pump 230. The discharge end of pump 230 is connected through a line 232 to the intake end of pump 231. Another line 233 connects line 232 with the head end of cylinder 191 and supplies a small volume of fluid thereto at all times, which is the difference between the output of pump 230 and that of pump 231.

It should be noted here that lever 50 is moved in a clockwise direction while lever 40 remains stationary in its right-hand position. This movement of lever 50 while pin 42 in lever 40 remains stationary causes spring 58 to be placed in tension against pin 56.

When valve 30 moves to the right, the connection between lines 31 and 32 is blocked so that fluid under pressure will not be conducted to both sides of cylinder 12. At the same time the left-hand section 23 of reversing valve 20 directs fluid under pressure from line 126 through lines 128 and 129, valve 130 and line 131 to left-hand section 33 of valve 30. With valve 30 in the right-hand position, fluid from line 131 is directed through line 132 to the left-hand end of valve 110, shifting said valve to the right to connect line 145 with line 148 leading to valve 104, which connects said line and, therefore, the head end of cylinder 107 with an exhaust passage.

The head end of cylinder 107 being thus connected with an exhaust line, the fluid under pressure always available in line 140 at the other end of said cylinder moves piston 106 to the right until stopped by adjusting screw 109. This permits the above-described action by which plunger 53 engages the first notch in the spacing bar.

After carriage 10 has been positioned for the grinding of the first cam, timer 118 may be started by any suitable means, such as movement of wheel base 181 to grinding position, to determine the duration of the grinding operation or any part thereof.

At the end of the predetermined period, said timer deenergizes solenoid 116; and valve 115 is moved to the right by spring 117. In this position of valve 115, the fluid under pressure in line 141 is directed through line 142, check valve 143, and line 144 to the right-hand end of

cylinder 107, moving piston 106 to the left. This movement of piston 106 causes arm 103 and associated parts to be rotated in a clockwise direction to withdraw plunger 53 from the first notch 60 in spacing bar 61 and also to shift valve 104 to the left against spring 108.

In the left-hand position of valve 104, fluid under pressure from line 123 is directed through line 240, line 241 to the rod end of both of the cylinders 190 and 191 to cause withdrawal of wheel support 181 from grinding position and resetting of slow feed piston 191. Fluid under pressure from line 240 also passes through line 242 to dresser valve 98. However, no dressing operation occurs until all the cams on a shaft have been ground, at which time valve 98 is shifted by solenoid 95. This operation will be described later.

The clockwise movement of lever 100 also serves to shift yoke 160 to the left. Near the end of its movement in this direction, said yoke picks up the head of adjusting screw 161 in valve stem 162 and shifts said valve to the left-hand position shown. In this position, fluid under pressure from line 210 is directed through line 250 to the upper end of cylinder 195, moving piston 196 downwardly so that piston rod 198 engages bracket 200 on slide 182, shifting said support in a clockwise direction in the position shown in the drawing. In this position, grinding wheel 180 will grind the next cam on the shaft to a surface tapered in the opposite direction to that of the first cam.

Because of the tension in spring 58, lever 50 is rotated in a counterclockwise direction about its pivot 51 to shift valve 20 to the right and sliding member 52 and plunger 53 to the left out of alignment with the notch from which it has just been withdrawn. The previously described indexing movement is repeated, carriage 10 moving again to the right until the plunger drops in the next notch. The next notch 60 is not as deep as the first notch 60', and as portion 59 of plunger 53 drops into notch 60, lever 100 moves in a counterclockwise direction; but because of the fact that notch 60 is not as deep as notch 60', the movement of said lever is limited so that it does not move far enough to shift valve 163, which remains in the left-hand position.

After grinding the last cam on a shaft, lever 40 is moved manually to the left-hand position. This movement releases headstock limit switch 81, shifts valve 30 to the left-hand position and puts spring 57 in tension. Valve 20 remains in central position.

Opening switch 81 deenergizes relay 82 and opens the circuit to motor 82 through contact 84.

As carriage 10 moves into position to grind the last cam, dog 90 on said carriage engages dresser limit switch 91, energizing relay 92 and closing contacts 93 and 94. Closing contact 94 completes a circuit parallel to that through contact 84 and maintains motor 82 in operation after the contact 84 has been opened. When carriage 10 returns to its left-hand position switch 91 is released and motor 82 stops.

Contact 93 completes a circuit to dresser solenoid 95 to initiate a wheel dressing operation similar to those described in the above-mentioned patents. Said solenoid shifts a valve 98 to direct fluid under pressure through a reversing valve 99 alternately to opposite ends of a dresser cylinder 111. A piston 112 in said cylinder has a piston rod 113 on which a dressing diamond 114 is mounted for dressing the grinding wheel 180.

However, fluid for actuating piston 112 is not available until valve 104 is shifted to the left upon withdrawal of plunger 53 after the last cam on a shaft has been ground. In this position of valve 104, fluid is directed through line 240 and 242 to said dressing mechanism.

With valve 30 in the left-hand position, the connection between lines 31 and 32 is blocked so as to cause fluid under pressure to flow through line 21 to the right-hand end of cylinder 11. Also in this position the left-hand section 33 of valve 30 blocks line 131, preventing flow of fluid under pressure to the left end of valve 110 so that said valve remains in the position shown.

When timer 113 functions at the end of the grinding operation on the last cam, valve 115 is returned to the right-hand position, directing fluid under pressure through line 142, check valve 143, line 144 to the head end of cylinder 107, moving piston 106 to shift valve 104 to the left and withdraw plunger 53 from spacing bar 61. The withdrawal of said plunger permits spring 57 to shift lever 50 in a clockwise direction, moving valve 20 to the left and directing fluid under pressure from line 121 through line 21 to the right-hand end of cylinder 11. Piston 12 and carriage 10 move to the left, but plunger 53 is prevented from dropping into the notches 60 during this movement because valve 110 has remained in the right-hand position, thus maintaining pressure of fluid on the head end of cylinder 107 through lines 144, 145 to valve 110 and from valve 110 to line 148 to the exhaust connection in valve 104. The carriage, therefore, continues to move to the left until plunger 53 is engaged by stop 62, shifting said plunger slightly to the left, and through sliding member 52, rotating lever 50 in a counter-clockwise direction to return valve 20 to a neutral position and thus shut off the supply of fluid to cylinder 11.

When carriage 10 begins to move to the left, limit switch 91 is released, opening contacts 93 and 94. Opening contact 94 breaks the circuit to motor 82. However, contact 94 is by-passed through contact 96, which is actuated by a cam 97 on the headstock spindle. This cam engages the contact only when the cradle has been dropped to inoperative position, as described in Patent 2,243,410 granted May 27, 1941.

While the apparatus described above is specifically for grinding successive cams having oppositely tapered surfaces, it is to be understood that it may be adapted to the grinding of cam shafts on which oppositely tapered cams are irregularly distributed without departing from the spirit of the invention.

We claim:

1. In a machine of the kind described having a bed, a grinding wheel support, a grinding wheel rotatably mounted thereon, a work support, said supports being mounted on said bed, means for effecting relative longitudinal movement between said supports, means to effect said movement intermittently to successively position said grinding wheel and spaced portions of a work piece in operative relation, means for swiveling said grinding wheel about a vertical axis including a hydraulic motor, and means for actuating said swiveling means in timed relation with the intermittent movement of said carriage, including a spacing bar in said carriage having deep and shallow notches spaced in accordance with the spacing of the portions to be ground, a plunger for successively engaging the notches in said spacing bar, and control means actuated in conjunc-

tion with said plunger for causing said motor to move in opposite directions to position said grinding wheel for grinding oppositely tapered cams.

2. In a machine of the kind described having a bed, a grinding wheel support, a grinding wheel rotatably mounted thereon, a work support, said supports being mounted on said bed, means for effecting relative longitudinal movement between said supports, means to effect said movement intermittently to successively position said grinding wheel and spaced portions of a work piece in operative relation, means for swiveling said grinding wheel about a vertical axis including a hydraulic motor, and means for actuating said swiveling means alternately in opposite directions in timed relation with the intermittent movement of said carriage, including a spacing bar on said carriage having deep and shallow notches spaced in accordance with the spacing and direction of taper of the portions to be ground, a plunger for successively engaging the notches in said spacing bar, and control means including a reversing valve connected to said plunger, said plunger being operable when moved into a deep notch for causing said motor to move in one direction and, upon withdrawal from said deep notch, to cause said motor to move in the opposite direction.

3. In a machine of the kind described having a bed, a grinding wheel support, a grinding wheel rotatably mounted thereon, a work support, said supports being mounted on said bed, means for effecting relative longitudinal movement between said supports, means to effect said movement intermittently to successively position said grinding wheel and spaced portions of a work piece in operative relation, means for swiveling said grinding wheel about a vertical axis including a hydraulic motor, and means for actuating said swiveling means alternately in opposite directions in timed relation with the intermittent movement of said carriage, including a spacing bar having notches spaced in accordance with the spacing of the portions to be ground, a plunger for successively engaging the notches in said spacing bar to locate said portions in operative relation to the grinding wheel, and control means including a reversing valve connected to said plunger for causing said motor to move alternately in opposite directions.

4. In a machine of the kind described having a bed, a grinding wheel support, a grinding wheel rotatably mounted thereon, a work support, said supports being slidably mounted on said bed, means for effecting relative longitudinal movement between said supports, means to effect said movement intermittently to successively position said grinding wheel and spaced portions of a work piece in operative relation, means for swiveling said grinding wheel about a vertical axis including a hydraulic motor, means for actuating said swiveling means alternately in opposite directions in timed relation with the intermittent movement of said carriage including a spacing bar having notches spaced to locate said portions in operative relation to the grinding wheel, a plunger for successively engaging said notches in said spacing bar, control means including a reversing valve for causing said motor to move alternately in opposite directions, and a lost motion connection between said reversing valve and said plunger for preventing operation of said reversing valve in predetermined positions of said carriage.

5. In a machine of the kind described having a bed, a grinding wheel support, a grinding wheel

rotatably mounted thereon, a work support, said supports being mounted on said bed, means for effecting relative longitudinal movement between said supports, means to effect said movement intermittently to successively position said grinding wheel and spaced portions of a work piece in operative relation including a locating mechanism for controlling said longitudinal moving means, means for swivelling said grinding wheel support about a vertical axis including a hydraulic motor, and means including a valve actuated by said locating means for causing said hydraulic motor to move in opposite directions to

position said grinding wheel for grinding oppositely tapered cams.
